UNITED STATES PATENT OFFICE.

HERMANN BENSMANN, OF MINSTER, OHIO.

WINDMILL.

SPECIFICATION forming part of Letters Patent No. 293,704, dated February 19, 1884.

Application filed August 17, 1883. (No model.)

To all whom it may concern:

Be it known that I, HERMANN BENSMANN, a citizen of the United States, residing at Minster, in the county of Auglaize and State of Ohio, have invented certain new and useful Improvements in Windmills, of which the following is a specification, reference being had therein to the accompanying drawings.

This invention has relation to improvements in windmills; and it consists in the construction and novel arrangement of the same, all as will be hereinafter more fully explained, and particularly pointed out in the claims appended.

15 The annexed drawings, to which reference is made, fully illustrate my invention, in which—

Figure 1 represents a side view of my improved windmill. Fig. 2 is a sectional view of the wind-wheel, and Figs. 3 and 4 are other 20 detail views, and Fig. 5 is a perspective view of arm D.

Referring by letter to the accompanying drawings, A is the platform, which is elevated in the usual manner, and provided with the 25 stationary table A', that is supported upon legs or posts a, secured to the platform.

B designates a U-shaped frame, the cross-bar a' of which is provided with a downwardly-projecting tube, a², which is screw-threaded to 30 receive a nut, a³, whereby the U-shaped frame is secured to the stationary table. Said cross-bar has secured to its under side a plate, b, that rests on the stationary table and revolves thereon, carrying the said frame and mill therewith.

B' indicates the vertical shaft that extends from the ground up through the tube a², and is provided with a pinion, b', at its upper end, that engages a similar pinion, b², secured to a 40 horizontal shaft, b³, that has its bearings in the upright arms of the U-shaped frame. The forward end of the horizontal shaft b³ is provided with a gear-wheel, C, which meshes with a pinion, c, on a horizontal shaft, c', arranged 45 above the shaft b³, and having its bearings in the vertical arms of the U-shaped frame aforesaid.

C represents the wind-wheel, the hub d of which is provided with a rearwardly-projecting tube, d', on which the pinion c is secured, and between the hub and said pinion strad-

dles an arm, d², that is secured at its upper end to the vertical front arm of the U-shaped frame, as shown in the drawings, which arm secures the wheel to the frame and at the same 55 time allows said wheel to revolve.

On the outer end of the wheel-shaft c' is rigidly secured a disk, e, having extending therefrom radial arms e' e' e' e', the outer ends of which engage eyes e² e² on the rods e³ e³, which latter are provided with eyes f' f' at each end, to engage studs f' f' on the outer edge of the wheel-blades f² f², which rods e³ e³ connect all the blades to one another. The inner ends of the blades are provided with journals that have 60 their bearings in the hub of the wheel, and the outer ends of the blades have similar journals that have their bearing in the rim g' of said wheel, and the rim and hub are connected to one another by radial spokes g² g². The shaft 70 c' is provided with a longitudinal groove, h, that extends from the front vertical arm of the U-shaped frame to the outer end of the shaft, in which groove plays a stud or pin, h', that is secured to the hub of the wheel.

On the shaft c', between the two vertical arms of the U-shaped frame, is rigidly secured a collar, i, and between this collar and the rear arm of the U-shaped frame and encircling 75 said shaft c', is a coil-spring, i', that has its end bearings against said collar and the rear arm aforesaid.

D indicates a right-angular bar, the vertical portion k of which is bolted to the inner face of the front arm of the U-shaped frame, and the horizontal portion k' is provided with an eye, l, to which is pivoted one end of a slotted bar, l', which is arranged in front of the collar on the shaft c', and said shaft passes through and works within the slot of said bar 90 l'. The opposite end of the bar l' to that of the pivoted end is provided with perforations m m', to which is connected one end of a rod, m', while the opposite end of said rod is connected to a wing, E, that is hinged at its lower 95 end to bar n, secured to the vane E'. The rod m' is connected by its hooked end n' to one of the perforations in the arm or bar l' while its opposite hooked end is connected to an eye, p, in the end of a bar, p', that is secured to the 100 vane E', as shown. The forward end of said vane is pivoted by a vertical bolt, p², between

the upper and lower arms, $r r$, of a **U**-shaped bracket, s , which bracket is secured to the rear vertical arm of the **U**-shaped frame.

F indicates a bar secured at its rear end to the vane E', and provided with an eye, s' , in its forward end, to which is connected one end of a rod, t , while the opposite end, t' , of said rod connects with the upper end of a vertical rod, w , the end t' of which is bent at right angles to the vertical rod w , which rod passes through the tube a^2 and extends to the ground, and its lower end is also bent at right angles to said vertical rod w , and serves as a lever to operate the vane through the medium of the connecting-rod t .

It will be observed that the operation of my windmill is automatic, and that the speed can be regulated evenly. Should the wind be too strong, the wing E is struck by the same and forced rearwardly, and by means of the rod m' , connected thereto, the bar l' is carried therewith, and by the same pressing upon the collar of the wheel-shaft said shaft is drawn rearwardly, and thus through the medium of the radial arms $e' e' e' e'$ closes the blades of the wind-wheel, and when the wing is relieved from pressure the spring on the wheel-shaft forces the blades out to their normal position, and at the same time the vane E' is also thrown in and out of operation with the wind through the medium of the rod m^2 , which is connected at one end to the slotted arm l' and at the opposite end to the bar p' , secured to the vane E'.

When it is desired to use the device for running machinery where a regular speed is required, the connecting-rod m^2 is to be detached from the vane E' and bar l' , and the vane is thrown in and out of the wind by means of the vertical rod w through its connecting-rod

t , that is attached to the bar F on the vane 40 aforesaid. This operation is effected by the operator standing on the ground.

The lower end of the vertical shaft is to be provided with suitable gearing, belting, &c., for operating pumps, machinery, &c., which 45 latter may be placed near the windmill or at a distance.

Having described my invention, what I claim, and desire to secure by Letters Patent, is—

1. The combination, in a windmill, of the 50 wheel-blades $f^2 f^2$, connected to one another by the rods $e^3 e^3$, having eyes in each end to engage the studs $f' f'$, the arms $e' e'$, secured to the rods $e^3 e^3$, and disk e on the end of the shaft e' , which latter is provided with the groove h , 55 to engage the pin h' in the hub of the wheel C', of the pivoted slotted bar l' , shaft c' , spring i' , connecting-rods $m' m^2 t$, gear-wheel C, pinions $e b' b^2$, wing E, vane E', **U**-shaped frame B, and stationary table A', as shown and de- 60 scribed.

2. The combination, in a windmill, of the **U**-shaped frame B, provided with bearings for the horizontal shafts $e' b^3$ of the stationary table, supported upon the posts $a a$, the vertical 65 operating-rod w , bent at its upper and lower ends at right angles thereto, of the connecting-rods, gear-wheels, pinions $e b' b^2$, slotted bar l' , shaft c' , spring i' , wing E, vane E', and wind-wheel C', constructed as described, the 70 whole as shown and set forth.

In testimony whereof I affix my signature in presence of two witnesses.

HERMANN BENSMANN.
